UNITED STATES PATENT OFFICE.

WILLIAM J. ORR, OF CHICOOPEE, MASSACHUSETTS, ASSIGNOR TO A. G. SPALDING & BROS., OF JERSEY CITY, NEW JERSEY, A CORPORATION OF NEW JERSEY.

TENNIS-BALL AND PROCESS OF MAKING SAME.

1,376,778.

Specification of Letters Patent.

Patented May 3, 1921.

Application filed August 5, 1919. Serial No. 315,508.

To all whom it may concern:

Be it known that I, WILLIAM J. ORR, a citizen of the United States, resident of Chicopee, Massachusetts, have invented certain new and useful Improvements in Tennis-Balls and Processes of Making Same, of which the following is a specification.

My invention has for one of its objects to protect the seam of the fabric cover of a tennis ball.

As is well known to tennis players, the edges of the seam sometimes open and curl up after the ball has been in play and this interferes with the flight of the ball and 10 renders it unfit for accuracy in play.

With a sewed seam the impact of the racket during hard play is apt to cause the seam to open as stated before. With my improvement the cover can be cemented in place 20 on the rubber center, no sewing of the seam being required, and the seam will be protected against damage and the life of the ball will be increased.

In carrying out the invention the fabric 25 cover is compressed at separated points along the seam, and thus permanent depressions are provided alternating with portions of the full thickness of the cover so that the depressed areas are protected from the 30 strokes of the racket.

As these depressed portions in the aggregate extend along a considerable length of the seam, say one-half or more and as they are protected by the adjacent raised portion 35 or portions of the full diameter, the edge of the seam along these depressions forms a uniting means of considerable extent and which is protected from the strokes of the racket and from direct contact with the 40 ground, and thus provides what may be termed sealing areas which will keep the cover securely united with the rubber center, the sealing areas being as stated protected from direct contact with the racket and 45 ground.

Other features of the invention will be clear from the following description.

In the accompanying drawing:

Figure 1 is an elevation of a fabric covered tennis ball embodying my invention.

Fig. 2 is a sectional view of my improved tennis ball.

In these drawings 1 is the hollow rubber center of substantially ordinary form. 2 is 55 the fabric cover. This fabric cover, when

new, has a nap or loose fiber surface which acts to control the flight of the ball. In play, however, this nap soon wears off and this controlling factor then is lost.

With my improvement, however, the function of the fibrous surface so far as controlling the flight of the ball is concerned, will still be performed after the ball becomes worn because of the presence of depressions 3 in the surface of the fabric cover, said depressions being distributed over the entire surface of the ball in order to get this controlling effect.

The depressed portions of the fabric also perform another important function in providing protected sealing means for uniting the cover with the rubber center. For this purpose the depressions include portions of the edges at the seam. In the particular construction shown these depressions 75 cross the seam as shown at 4 and preferably they are bisected by the seam so that equal areas of the depressed portions will lie on opposite sides of the seam. These depressed portions will be protected from frictional 80 contact of the racket and of the ground because they are surrounded by portions of the cover of the full thickness and these will in affect protect the sealing areas at separated points along the seam and thus a cemented seam may be employed and a durable ball provided, thus dispensing with the sewing operation and also dispensing with the liability of the sewed seam to open up 85 because of the breaking of the thread due 90 to the cutting action of the racket or contact with the ground.

I am aware, of course, that golf balls are provided with dimples or pits to control the flight, but so far as I know, a fabric covered 95 tennis ball having depressions in the fabric surface has never been proposed heretofore.

In order to provide the ball of the construction above described having the rubber center of substantially ordinary form and a 100 fabric cover with separated depressed areas in its fabric surface, a special course of manufacture is employed and in carrying out this special method, the rubber center is first molded in a smooth spherical shape. 105 This center is then covered with cement. The felt cover is died out of proper shape and is likewise covered on the inside with cement and placed in position on the rubber center. The ball is then placed in a two 110

piece mold which has a negative of the surface markings desired to be provided in the felt cover. The felt being of standard thickness greater compression is obtained over 5 certain parts of the fabric by reason of the protruding surface or projections on the mold, and in this way the felt is permanently compressed to form the depressed areas.

10 I claim as my invention:

1. A tennis ball having a hollow rubber center with a fabric cover, said fabric cover applied directly to the rubber having depressions molded in its surface, substantially 15 as described.

2. A tennis ball having a hollow rubber center with a fabric cover, said fabric cover applied directly to the rubber having spaced apart depressions molded in its outer surface 20 along the seam, substantially as described.

3. A tennis ball having a hollow rubber center with a fabric cover, said fabric cover applied directly to the rubber having depressions 25 molded in its outer surface spaced apart along the seam, said depressions ex-

tending across the seam, substantially as described.

4. A tennis ball having a hollow rubber center with a fabric cover, said fabric cover 30 applied directly to the rubber being compressed by molding at certain points forming depressions and leaving intermediate raised portions, substantially as described.

5. A tennis ball having a hollow rubber 35 center with a fabric cover cemented thereon and with depressions molded in the fabric cover, substantially as described.

6. A tennis ball having a hollow rubber center with a fabric cover cemented thereon, 40 and with depressions molded in said fabric cover spaced apart along the cemented seam, substantially as described.

7. The herein described method of making a tennis ball consisting in covering a rubber 45 center with fabric cemented thereto and then subjecting the ball to a molding action within a mold having projections on its interior surface to compress the fabric cover at separated areas, substantially as described. 50

WILLIAM J. ORR.
